CLAIM

The ornamental design for a tackle bag with hooks and saddle bags, as shown and described herein.

DESCRIPTION

FIG. 1 is a front view of the tackle bag with hooks and saddle bags;

FIG. 2 is a rear view of the tackle bag and saddle bags;

FIG. 3 is a left side view of the tackle bag with hooks and saddle bags;

FIG. 4 is a right side view of the tackle bag with hooks and saddle bags;

FIG. 5 is a top view of the tackle bag with hooks and saddle bags;

FIG. 6 is a bottom view of the tackle bag with hooks and saddle bags;

FIG. 7 is a left side perspective view of the tackle bag with hooks and saddle bags;

FIG. 8 is a right side perspective view of the tackle bag with hooks and saddle bags;

FIG. 9 is a front perspective closed interior view of tackle bag with hooks and saddle bags; and,

FIG. 10 is a front perspective open interior view of tackle bag with hooks and saddle bags.

The various unshaded components shown outlined in broken lines illustrate environment that forms no part of the claimed design. Additionally, broken lines on shaded areas show illustrative examples of stitching that form no part of the claimed design.

1 Claim, 10 Drawing Sheets
